Atty.

UNITED STATES PATENT OFFICE.

JOSEPH SYLVAN, OF CHICAGO, ILLINOIS.

BUILDING-VENTILATOR CONSTRUCTION.

Application filed April 26, 1921. Serial No. 464,650.

To all whom it may concern:

Be it known that I, JOSEPH SYLVAN, a citizen of the United States, and a resident of Chicago, in the county of Cook and State 5 of Illinois, have invented certain new and useful Improvements in Building-Ventilator Constructions; and I do hereby declare that the following is a full, clear, and exact description thereof, reference being had to 10 the accompanying drawings, and to the letters of reference marked thereon, which form a part of this specification.

This invention relates to improvements in building ventilator construction, and consists of the matters hereinafter described and more particularly pointed out in the appended claims.

The invention relates more particularly to that type of building ventilator known as a 20 "ridge ventilator," wherein there is provided in the ridge or peak of a building roof or skylight, an elongated rectangular opening, above which is a hood or secondary roof structure, the margins of which overhang 25 the sides of said opening. Thus, when a wind blows beneath one or the other side margins of the hood and over the ventilation opening, a suction is produced up through the opening to efficiently ventilate the space 30 beneath the roof or skylight.

One of the objects of the present invention is to provide in connection with such a ventilator, a plurality of deflector plates arranged longitudinally of the opening to prevent a down draft, or the entrance of rain, snow and the like, through said opening, into the room or space beneath the same without materially restricting the up draft through said opening due to the suction or 40 aspirating action of the wind as before mentioned.

A further object of the invention is to so construct said defectors that such rain as is blown in upon them, is collected and 45 drained towards the ends thereof and thereafter discharged out upon the roof.

A further object of the invention is to so construct the said defectors that they may be actuated from inside the building to substantially close said opening when it is so desired, without affecting the drainage before mentioned.

Other objects of the invention, as well as the many advantages thereof, will more fully 55 appear as I proceed with my specification.

In the drawings:

Figure 1 is a transverse section through the ridge or peak of a building roof embodying my improved ventilator construction.

Figure 2 is a vertical detail sectional view 60 on an enlarged scale on the line 2-2 of Figure 1.

Figure 3 is a view in elevation of a deflector actuating frame which will be more specifically referred to later.

Figure 4 is a perspective view of a fragment of one of the deflectors.

Referring now in detail to that embodiment of the invention illustrated in the accompanying drawings:—5 indicates a part 70 of the building roof, and 6 indicates the hood spaced above the same at the ridge thereof. As shown in this instance, the roof and hood are made of wood, but other material may be used in place of wood without departing from the spirit of the invention.

The roof includes transversely extending rafters 7, which are inclined downwardly and outwardly from the ridge and are connected together at points spaced from the ridge by horizontal cross braces 8. Spaced at equal distances on each side of the ridge or the junction of the rafters, and secured to said rafters, are longitudinally extending, 80 edgewise arranged stringers 9, and upon the rafters 7 outside of the plane of said stringers, is nailed the sheathing or boarding 10 of the roof. Upon the sheathing is laid the prepared waterproof or composition roofing material 11, the marginal parts 90 of which are attached to the outer faces of the stringers. A combined flashing and gutter strip 12, preferably of sheet metal, covers the stringers 9. The outer marginal part 13 of the strips overlaps the roof sheathing 95 near the stringers, and the inner marginal part 14 of the strips is spaced from the stringers 9, and is engaged upon the edges of the rafters to provide gutters 15 which are open at the ends. It is apparent that a space or opening is formed at the ridge of the roof, the sides of which are defined by the stringers 9, and the strips 12.

16 indicates one of plurality of upright standards arranged in the plane of the ridge or junction of the rafters. Said standard as shown, is secured at its bottom end to the cross brace 8 and projects at its top end a suitable distance above the ridge of the roof. Secured to the rafters 7 and the stringers 9 105

110

respectively, are upwardly and outwardly extending scantlings 17 arranged at a right angle to the rafters. Holes are provided in the flashing and gutter strips 12 through 5 which the bottom ends of the scantlings 17 extend. Fixed to the top ends of the scantlings, and to the top ends of the standards 16, are secondary or hood rafters 18, which extend in planes parallel to the roof rafters 10 7. To the top outer edges of the scantlings 17, and to the outer ends of the hood rafters 18, are longitudinal stringers 19, which are arranged in a plane spaced outwardly from the vertical plane of the roof stringers 9.

15 To more securely tie the hood rafters and standards together, I provide horizontally disposed secondary cross braces 20. On the hood rafters is nailed a roof sheathing 21, upon which is laid a prepared waterproof 20 roofing material 22. The structure just above described provides a hood which is spaced above, and overhangs at its sides, the opening in the roof proper. End walls 23 are provided between said hood and roof.

25 It is apparent from the foregoing that the roof opening communicates with the openings defined by the outer side margins of the hood and the stringers 9 and the combined flashing and gutter strips 12, of 30 the roof, so that the wind is free to blow through the hood openings and over the roof opening. When the wind is blowing in through one hood opening and out through the other, an aspirating or suction 35 action is established above the roof opening to produce an updraft therethrough which ventilates the space beneath the same.

To prevent a down draft through the ventilating or roof opening as well as to keep 40 out the rain and snow and to increase the entrance of natural light through said opening, without restricting or materially reducing the area of the said ventilating opening, I provide the following construction:

45 25, 25, indicate a plurality of normally upright deflector plates, extending longitudinally of the ventilating or roof opening. Said plates are arranged in sets, one 50 set on each side of the plane of the ridge of roof. As illustrated herein, each set includes four deflector plates, but this number may be increased or decreased according to the width of the roof opening. The 55 plates of each set rest upon and are connected to the roof rafters, and are laterally spaced apart a substantially equal distance between each other, which distance is shorter than the height of said plates. The 60 innermost plates of each set are spaced from the ridge a distance substantially equal to the height of the plates. As shown, the outermost plates of each set are arranged in the plane of the margins 14 of the flashing and gutter strips 12.

As said deflector plates are all alike, a detail description of one will suffice. Each plate includes an upright panel 26 having a downwardly and outwardly bent bottom web 27 that terminates in an upright flange 70 28, which is spaced from the panel to provide a trough or gutter 29 at the bottom of the deflector plate. The web 27 is inclined in a plane parallel to the inclination of the roof rafters 7. 75

Each deflector plate extends substantially the full length of the roof opening, to terminate short of the end walls 23 for a purpose to appear later, and each plate, except the outermost one of each set, is hinged along the bottom marginal part of the panel as at 30, to the roof rafters 7. The outermost plate of each set which normally stands in the plane of the flanges 14 of the flashing and gutter strips 12 is hinged to the flanges 80 14 of said strips in the same manner. The panels of the deflector plates are of a height greater than the spacing distance between said plates, so that when the plates are swung inwardly and downwardly about the 85 hinged connection 30, the top marginal part of one plate overlaps the gutter part 29 of the next inner adjacent plate. The top edges of the innermost plates of each set 90 approximately engage each other in the plane of the ridge of the roof, and at the junction of the rafters 7 I provide blocks 31 which have oppositely inclined surfaces upon which the top marginal parts of the innermost deflector plates of each set rest 95 when in the closed position shown in dotted lines in Figure 1. It is apparent from the foregoing that when the said plates have been swung inwardly and downwardly, they will act to close the ventilation opening in 100 the roof and if any rain blows in beneath the side margins of the hood and falls upon the deflector plates, the troughs 29 will catch and direct the same towards the ends of the deflector plates, where it will drop into 105 transverse gutters 32 fixed on the inside surface of the end walls 23. The gutters 32 are slightly inclined downwardly from the middle towards the ends which communicate with discharge tubes 33 that open 110 through the roof sheathing. Thus, such water as is discharged from the ends of the gutters of the deflector plates and from the gutters 15 of the flashing strips 12, falls into the gutters 32 to be discharged out upon 115 the roof. 120

When the deflector plates are in their upright position, the top edge of one plate is arranged in a plane above that of the gutter 125 29 of the next adjacent plate, the top edges of the outermost plates of each set extending into a plane below that of the side margins of the hood, and the top margins of the innermost plates of each set extending 130 into a plane above that of the side margins

of the hood. Thus such wind as blows in horizontally beneath one side margin of the hood will strike the outermost deflector plate and be deflected upwardly to the top margins of the next plate so that it will pass over the roof opening and out beneath the other side margin of the hood, thus producing an up draft through said opening.

If the wind should enter at an angle inclined downwardly from the horizontal, the said plates will deflect the same and change its course so that it must pass over and can not pass down through the roof opening.

Means are provided for simultaneously swinging all of said plates from an upright open, to an inclined closed position, and such means is as follows. On one or more of the uprights 16 between the end walls 23, are mounted flat triangular frames 35. Each frame includes a vertically arranged flat bar 36, having spaced slots 37 therein, two oppositely downwardly and outwardly inclined bars 38, arranged in planes parallel with the roof rafters 7, and a horizontal cross bar 39 which connects the outer ends of the bars 38 with the vertical flat bar 36 see Fig. 3. Extending through the slots 37 and secured in the associated upright 16, are lag screws 40, which connect the frames to said uprights in a manner permitting of a limited vertical movement of the frames. Pivotally connected to the inner face of the panel 26 of each deflector plate 25, is the top end of a link 41, the bottom end of which is connected to the inclined bars 38 of each frame 35 at points spaced apart a distance equal to the spacing between the deflector plates.

The bottom end of each vertical bar 36 of each frame 35, is connected to one end of a link 43, the other end of which is pivotally connected to the free end of a short arm 44 secured to a shaft 45, journalled in bearings 46, on the bottom edges of the cross bars 8, at the bottom ends of the uprights 16. Said bearings are adjustable to grip the shaft so that the same is not easily rotatable in said bearings. Fixed to the shaft between its ends is a sheave 47, about which is trained an endless operating chain 48, the bottom looped end of which hangs in a position within convenient reach, from the floor of the room or space beneath the roof opening.

It is apparent that by rotating the shaft 45 in one direction (counter clockwise substantially 90°) the frame 35 is moved downwardly and through the links 41 will swing all the deflector plates 25 inwardly and downwardly as shown in dotted lines in Figure 1 wherein the opening in the ridge of the roof is closed.

When the shaft 45 is rotated in the other or clockwise direction, the frame 35 is elevated and this through the links 41 will swing the deflector plates into the upright

position shown in full lines in Figure 1. When the deflector plates are in this position, the arm 44 will have swung a short distance beyond the vertical plane of the shaft 45, where it will engage against and be stopped by a stop pin 49. Thus the deflector plates are automatically locked in their upright open position and cannot be blown down into a closed position by a strong wind blowing in beneath one or the other margins of the hood.

Instead of the stationary hood structure as illustrated and described herein, I may use the deflector plates equally as well in connection with a hood wherein the side sections are of the hinged type as shown in my Patent Number 1,410,625, dated March 28, 1922.

The deflector plates not only act to prevent downdraft through the roof opening, but also act to reflect the natural light so that it is spread over a greater area in the room or space beneath the roof opening.

While in describing my invention I have referred to certain details of mechanical construction and arrangement of parts, I do not wish to be limited thereto except as pointed out in the appended claims.

I claim is my invention:—

1. In combination with a roof having a ventilation opening therein and including roof rafters, a hood above said opening, a plurality of deflector plates extending longitudinally of said ventilation opening, each plate having a trough at its bottom margin, means providing a hinged connection between said bottom margins of said plates and said roof rafters, and means for simultaneously swinging said plates from a closed position wherein they extend at an angle substantially parallel with the roof rafters into the open position wherein they stand substantially upright.

2. In combination with a roof having a ventilation opening therein and including roof rafters, a hood above said ventilation opening, two sets of longitudinally extending deflector plates, arranged with one set on each side of the vertical plane of the ridge of the roof, means providing a hinged connection between the bottom margins of the deflector plates and said rafters, each set of plates being capable of a swinging movement from the upright open position, downwardly and inwardly toward said plane of the ridge of the roof into a closed position wherein they extend parallel to the plane of the rafters, a vertically movable frame, means connecting each deflector plate to said frame, and means for imparting a limited vertical movement to said frame for swinging the deflector plate from an open to a closed position and vice versa.

3. In combination with means providing a ventilation opening, a hood above said

opening, and a plurality of normally upright, hinged deflector plates extending longitudinally of said opening, each plate including an outwardly facing trough at its bottom edge, a vertically movable frame, means connecting the frame and the deflector plates, and means for imparting movement to said frame to swing said deflector plates about the hinged axes.

In testimony that I claim the foregoing 10 as my invention, I affix my signature in the presence of two witnesses, this 12th day of April, A. D. 1921.

JOSEPH SYLVAN.
